WILLIAM F. EAMES, OF WILKINSBURG, PENNSYLVANIA, ASSIGNOR TO WESTINGHOUSE ELECTRIC & MANUFACTURING COMPANY, A CORPORATION OF PENNSYLVANIA

ELEVATOR CONTROL SYSTEM

Application filed April 5, 1928. Serial No. 267,711.

My invention relates to motor-control systems and has particular relation to elevators, hoists and similar machinery.

An object of my invention is to provide a control system for motors wherein a motor may be accurately stopped at any predetermined point in its travel.

Another object of my invention is to provide a control system for an elevator motor wherein the elevator may be stopped accurately level with the floor without overrunning or underrunning the floor.

Another object of my invention is to provide a control system for elevators of the Ward-Leonard type wherein the generator structure is modified to insure accurate speed regulation of the motor at low speeds independent of loading conditions.

Another object of my invention is to provide a system, as described in the preceding paragraph, wherein the commutating poles of a generator may be so arranged as to achieve an effect of cumulatively compounding the generator at such times as the generator is operating at low voltages and low currents.

In elevator systems controlled by means of variable-voltage equipment for use in modern installations, it is desirable that the elevator speed shall be regulated within comparatively narrow limits, independent of the load upon the elevator, since, in high-speed elevator work, the accuracy of landing is primarily based upon accuracy of speed regulation, that is, the normal speed of the elevator should be the same, regardless of the load thereon, when operating under predetermined conditions of control.

To accomplish this result, the Ward-Leonard or variable voltage system of control has been devised wherein variations in the speed of the motor which would normally occur with variations in the load upon the elevator are compensated for by means of cumulatively compounding the generator to produce such rising voltage characteristic on the generator as will compensate for the drooping speed characteristic of the motor.

The use of cumulative compounding of the

generator substantially accomplishes this result within rather wide ranges of load.

It has been observed, however, that a degree of generator compounding effective to provide satisfactory motor-speed regulation throughout the major portion of the load range, is ineffective to provide satisfactory regulation between motor-load values of from zero to a small percentage (usually approximately 10%) of full load. The observed variation in generator voltage has been found to increase, in accordance with load, to a maximum of several volts at the suggested percentage of full load.

When the elevator motor is operating at the slow speed required just prior to stopping at a floor, the voltage of the generator is correspondingly low, usually of the order of from 10 to 20 volts. At these low voltages, a variation in generator voltage of several volts is sufficient to cause a considerable percentage variation in motor speed, and corresponding variations in the point at which an elevator may be brought to rest.

In accordance with my invention, I propose to correct for the above noted discrepancies in generator voltage by imposing an additional degree of cumulative or differential compounding (depending upon the character of the load) on the generator throughout the suggested range of load values. As will be more fully described hereinafter, I effect this additional compounding of the generator by providing an additional component of commutating pole flux. By properly designing the magnetic circuit traversed by the commutating pole flux, I effect a cumulative compounding of the generator between the suggested positive load values and a differential compounding of the generator between the suggested negative load values, whereas, for load values throughout the remainder of the load range, the degree of compounding imposed by the commutating poles remains at a substantially constant value.

My invention will be described with reference to the accompanying drawing, wherein, Figure 1 is a diagrammatic view of an ele-

vator-control system of the Ward-Leonard type.

Fig. 2 is a diagrammatic view of the generator showing the arrangement of main poles and commutating poles, a portion of which view is in section, and

Fig. 3 is a diagrammatic view of a voltage curve obtained by the use of the generator hereinafter described.

Referring to the drawing, I have illustrated, in Fig. 1, an elevator car C supported upon a suitable cable Ca which passes over a hoist drum D to a suitable counterweight Cz. The hoisting drum D is illustrated as directly coupled to the armature EM' of a hoisting motor EM, the field winding EMF of which is connected for excitation by a suitable source of energy designated by conductors L1 and L2. The armature EM' of the motor EM is connected in loop circuit with the armature G' of a generator G. The generator G is provided with a separately excited field winding GF a series field winding GSF, a demagnetizing winding GAF, and a commutating pole winding GC. The generator G is driven by means of a suitable motor M, illustrated as of the shunt-wound type having its armature M' and its shunt field winding MF connected across line conductors L1 and L2.

The control of the direction and speed of the elevator car Ca is illustrated as of the usual type wherein up and down-direction switches 1 and 2, respectively, actuated by means of a car-switch Cs, control the direction of current supplied to the separately excited field winding GF of the generator G, while a speed switch 3, controlled by the car switch Cs, is arranged to control the value of the current supplied to the field winding GF.

Referring to Fig. 2, the generator G, the structure of which per se is claimed in my copending application, Serial No. 560,694, filed September 2, 1931 as a division hereof, and assigned to the Westinghouse Electric and Manufacturing Company, is illustrated diagrammatically as of the four-pole type, wherein the main poles are designated by the reference characters 5, 6, 7 and 8, respectively. Suitably located between the main poles 5, 6, etc., I have illustrated commutating or inter poles 9, 10, 11 and 12, it being understood that the number of inter poles corresponds to the number of main poles provided on the generator G. As is the usual practice in generators of this type, each of the inter poles is provided with a winding (one of which is designated by the character 13) suitably connected in series relation with each other and with the armature G'.

Each of the inter poles 9, 10, etc. may be provided with a core 14 suitably secured to the frame 15 of the generator G by means of a bolt 16. The core structure 14 and bolt 16,

as well as the frame structure 15, are all constructed of suitable magnetizable material. Interposed between the core member 14 and the frame 15, is a shim or washer 17 constructed of non-magnetizable material, for example, copper, brass or fiber. As is well known, the interposition of a section of non-magnetizable material between the frame 15 and the core member 14 constitutes the equivalent of an air gap between these members. Hence, a portion of the magnetic path through the inter pole 9 is constituted with a relatively small cross sectional area of low reluctance and a relatively large section of high reluctance.

The operation of my system will best be understood from an assumed operation of the elevator car C. Assuming that it is desired to move the car C upwardly, the car switch Cs may be moved in a counter-clockwise direction to energize up-direction switch 1 by means of a circuit which extends from line conductor L1 through conductors 20 and 21, contact members 22, 23 and 24 on car switch Cs, conductor 25, the coil of up-direction switch 1, conductors 26, 27, contact members 37' of an inductor relay 37, and conductors 39 and 40 to line conductor L2. Up-direction switch 1, when actuated, supplies current in one direction to the generator-field winding GF by way of a circuit which extends from line conductor L1 through conductors 29, contact members a of up-direction switch 1, conductor 30, separately excited field winding GF, conductor 31, resistor 32, conductors 33 and 34, contact members b of up-direction switch 1 and conductor 40 to line conductor L2. Generator G now supplies voltage to the armature of elevator motor EM, and the car C starts upwardly. The voltage supplied by generator G will be dependent upon the value of exciting current in the separately-excited-field winding GF with the addition of voltage induced by the cumulative-compounding effect of the series-field winding GSF. The effect of the winding GSF, since it is in series relation with the armatures G' and EM' of the generator and motor, respectively, will be greater or less dependent upon the load on the elevator car C at any given instant. An additional degree of generator compounding, also determined by the load on the elevator, is imposed by the commutating poles, as will be described more in detail hereinafter, in connection with Fig. 3. Hence, regardless of the load upon the elevator car C, the motor EM will be supplied with sufficient voltage to insure its operating at substantially constant speed for any given value of excitation current supplied to the separately-excited-field winding GF.

In the system described and illustrated, the control is of the ordinary inductor-landing type wherein slow down is automatically initiated and the car is brought to a stop, with-

out intervention on the part of the operator, by means of slow-down inductors 35 and 36 for the up and down directions, respectively, and stopping inductor 37.

5 When the up-direction switch 1 is actuated to close its contact members *a*, a self-holding circuit is completed thereby for maintaining the up-direction switch 1 in its actuated position until stopping inductor relay 37 opens 70 its contact members 37'. This holding circuit extends from a line conductor L1 through conductor 29, contact members *a* of up-direction switch 1, conductors 30 and 38, the coil of up-direction switch 1, conductors 26 and 27, normally-closed contact members 37' of stopping inductor relay 37, conductors 39 and 40 to line conductor L2. Hence, until 75 stopping inductor relay 37 is actuated, the up-direction switch will remain operative and 80 the car will continue its upward movement, even though the car switch *Cs* is centered.

If it is desired to move the car C at a greater speed, the car switch *Cs* may be moved to the left to its extreme position, supplying energizing current to speed switch 3 by way of a circuit which extends from line conductor L1 through conductors 20 and 21, contact members 22, 23 and 41 on car switch *Cs*, conductor 42, the coil of speed switch 3 and conductors 43 and 40 to line conductor L2. The actuation of speed switch 3 shunts 90 resistor 32 from the field-winding circuit by way of conductors 44 and 45, thus increasing the value of excitation current supplied to the separately-excited-field winding GF. Hence, the elevator motor EM will accelerate and operate at the speed corresponding to 95 this new value of field excitation.

When speed switch 3 is actuated, it completes a self-holding circuit for itself, which circuit extends from a line conductor L1 through conductors 29 and 46, contact members *b* of speed switch 3, conductor 47, contact members 35' of up slow-down inductor 35, conductor 48, contact members 36' of slow-down inductor relay 36, conductors 49 and 42, the coil speed switch 3 and conductors 43 and 40 to line conductor L2.

When it is desired to stop the elevator car, the car switch *Cs* will be returned to its central or illustrated off position. By reason of the holding circuits for up-direction switch 1 and speed switch 3, previously described, the car will continue its upward motion at high speed. Centering the car switch *Cs*, however, closes a circuit for energizing the actuating coils of inductor relays 35 and 37. This circuit extends from line conductor L1 through conductors 20 and 21, contact members 22, 23 and 50 on car switch *Cs*, conductor 51, the coil of stopping inductor relay 37, conductor 52, the coil of slow-down inductor relay 35, conductor 53, contact members *d* on up-direction switch 1 and conductors 54, 55 and 40 to line conductor L2.

As the car approaches the floor at which it is desired to stop, the slow-down inductor relay 35 will be brought adjacent an inductor plate 35" (one of which plates is provided at each of the floors past which the elevator moves) and the inductor relay 35, now energized, is actuated to open its contact members 35'. Opening contact members 35' releases the holding circuit for speed switch 3, which switch is restored to its normal condition, opening its contact members *a* and reinserting resistor 32 in circuit with the separately excited field winding GF to reduce the speed of the car in correspondence with the value of excitation current now supplied to field winding GF.

As the car approaches more closely to the desired floor, stop inductor relay 37 will be brought adjacent an inductor plate 37" associated therewith (one of which also is located adjacent each of the floors past which the car moves) and relay 37 will be caused to open its contact members 37' to release the holding circuit for up-direction switch 1. Up-direction switch will, when deenergized, 95 open the circuit for the partly excited field winding GF, and the car will be brought to a stop. It will be observed that, with the system of control just described, the elevator car C will be decelerated from its normal high speed to a landing speed prior to the final topping of the car. For accuracy in landing the car level, it will be apparent that the speed of the car at this low landing speed should be constant for all loads placed upon the car because the distance from the floor at which slow down and stop are initiated is fixed by the relative positioning of the inductor plates 35" and 37".

It will be observed that, under the conditions just described, contact members *c* of up-direction switch 1 will complete a circuit connecting the demagnetizing-field winding GAF across the terminals of the armature EM' of the elevator motor EM. The demagnetizing-winding GAF is so wound and arranged that, when connected across the terminals of the motor armature EM', the circulating current in the armature EM' will excite the winding GAF to oppose the effect of the separately excited and series field windings GF and GSF to thus reduce the voltage of the generator to zero and to thereby bring the elevator motor to a stop. It is assumed that, when the motor EM is brought to a stop, the usual mechanical brake (not shown) will be applied to maintain the car stationary.

Referring to Fig. 3, to illustrate the influence of my invention on a generator, I have shown characteristic voltage curves of a cumulatively compounded generator suitable for elevator applications, in which generator-voltage values are plotted as ordinates, 125 against generator load values, expressed in 130

percentages of full-load current, as abscissæ. The curves illustrate the variations in terminal voltage from a negative or overhauling load of approximately 50% full load to full load. The no-load voltage is shown as approximately 15 volts, which, as hereinbefore stated, corresponds to a typical "landing speed" of an elevator motor. Curve 56 is typical of a generator provided with normal compounding means, while curve 57 illustrates the improved voltage regulation effected in the practise of my invention.

Referring to curve 56, it will be observed that, throughout the load range from 10% to 100% full load in the positive direction, and from 10% full load to the extremity of the curve in the negative direction, the voltage of the generator is very nearly proportional to the load. Between the limits of a 10% positive load and 10% negative load, however, the slope of curve 56 is seen to depart from the substantially constant value noted with respect to the remainder of the load range.

For purposes of simplicity, I shall herein-after refer to that portion of the load range throughout which the slope of the curve is substantially constant as the "major portion" of the load range, and to that portion of the load range throughout which the slope of the curve departs from the desired or substantially constant value as the "restricted portion" of the load range.

Since the slope of curve 56 throughout the restricted portion of the load range differs from that throughout the major portion of the load range, it will be apparent that a degree of compounding effective to produce a desired "landing speed" of the elevator motor throughout the major portion of the load range, will be ineffective to produce the same motor speed throughout the restricted portion thereof. As noted hereinbefore, a small actual variation in generator voltage throughout the restricted portion of the load range, when the elevator motor is operating at the "landing speed", constitutes a considerable percentage variation.

Curve 57 represents a desirable voltage characteristic for a generator, in that the variations in generator voltage are substantially proportional to the generator load throughout the entire load range. By organizing a generator in accordance with my invention, the voltage characteristic thereof may be caused to take the form of curve 57.

By comparing curves 56 and 57, it will be seen that the slope of curve 56 may be corrected to conform to that of curve 57, by subjecting the generator to an additional component of excitation, the value of which varies as a function of the generator load throughout the restricted portion of the load range, and remains substantially constant throughout the major portion thereof. The

manner in which the described construction of the commutating poles of the generator is effective to produce this result may be set forth as follows.

To provide satisfactory commutating characteristics for the generator, the flux set up by the commutating pole windings should be substantially proportional to load throughout a predetermined range of load values, and should be of such a value as to substantially compensate, at the zone of commutation, for the flux set up by the current in the armature windings. If, now, the flux of the commutating pole windings is permitted to predominate, to a predetermined degree, over the flux set up by the current in the armature windings, the current in the commutated armature coils will be prematurely reduced to zero and reversed. The reverse current flowing in the commutated coils, of course, sets up a flux which is of such a direction as to add or subtract directly to or from the flux of the main field windings, and thus exerts a compounding action on the generator. It follows that this compounding action is cumulative when the load is positive, and differential when the load is negative, since the commutating pole windings carry the load current.

As described hereinbefore, this additional component of generator excitation should be proportional to load throughout the restricted portion of the load range, and should remain constant throughout the remainder thereof. In other words, the rate of increase of commutating-pole flux should be greater throughout the restricted portion of the load range than throughout the remainder thereof.

Referring again to the construction of the commutating poles, it will be observed that the magnetic circuit for the flux of the windings thereof comprises a main pole core, a connecting bolt, and a non-magnetic spacer. When both the pole core and bolt are unsaturated, it is apparent that a given increase in load current will produce a given increase in commutating-pole flux. If, now, the bolt is permitted to saturate at a predetermined value of load, it follows that subsequent increases in load will produce smaller increases in commutating-pole flux. In accordance with my invention, I permit the bolt to saturate at the point at which the slope of curve 56 assumes the desired value.

It will be seen, therefore, that, throughout the restricted portion of the load range, the commutating pole flux increases as such a function of the load as to perform not only its normal function, but to supply an additional component of main generator excitation in proportion to the load; that, throughout the major portion of the load range, by reason of the saturated condition of a portion of its magnetic circuit, the flux of the com-

mutating poles increases less rapidly, or, increases as such a function of the load that the additional component of generator excitation supplied thereby remains substantially constant. In accordance with my invention, therefore, when the load is positive or negative, the generator voltage corresponding to a particular load is increased or decreased to such an extent as to cause the actual voltage characteristic of the generator to assume a substantially constant slope throughout the entire load range.

It will, therefore, be observed that, by utilization of the structure just described, the inaccuracy of speed regulation at low speeds is corrected without disturbing the speed regulation normally imposed by the compounding of the generator G by means of the series field winding GSF.

In actual practice, it has been observed that the arrangement just described achieves an effect of correcting the inaccuracy of speed regulation to the extent of at least 50% and this amount of correction is readily appreciated when the control system herein described is applied to elevators having a device for automatically stopping the elevator car level with the floor, such as that herein described and also described in the copending application of E. M. Bouton, Serial No. 731,291, filed August 14, 1924, and assigned to the Westinghouse Electric and Manufacturing Company. With such automatic landing equipment, initiation of slow down at a definite distance from the floor, regardless of the load on the elevator, causes the car to stop substantially level with the floor without further attention on the part of the attendant. In actual test, such systems stop the car level with the floor within a half inch, regardless of load. However, by the use of the system for providing additional compounding of the generator, as herein described, such inaccuracy can be reduced to less than one-fourth of an inch.

Another method of accomplishing the result of effecting an equivalent of advancing the commutating plane is illustrated in Fig. 2 wherein the core 14 of the commutating pole is spaced from the frame 15 by a pair of lugs 60, formed integrally with the pole core 14 or introduced as spacers. This construction provides an air gap 61, and the pole operates in the same manner as described for the core 14. In this case, however, the bolt 16 should be constructed of non-magnetizable material.

My invention may be practiced in many ways, the embodiments herein described are illustrative only, and I do not desire to be limited to any of the details shown or described therein except insofar as defined in the appended claims.

I claim as my invention:

1. In a motor-control system, a motor, a

generator for supplying voltage to said motor, means for variably exciting said generator to cause said motor to be operated at speeds corresponding thereto and means for cumulatively compounding said generator between restricted load limits, said compounding means including a main-field-pole-supporting frame on said generator, commutating poles for said generator, a gap between said frame and said poles formed of non-magnetizable material and magnetizable means of less cross sectional area than said poles for bridging said gap.

2. In a motor-control system, a motor, a generator for supplying voltage to said motor, means for variably exciting said generator to cause said motor to be operated at speeds corresponding thereto, and means for cumulatively compounding said generator between restricted load limits, said compounding means comprising a main-field-pole-supporting frame on said generator, commutating poles on said generator spaced from their supporting frame by non-magnetic gaps and magnetizable means of predetermined flux-conducting capacity bridging said gap.

3. In a motor-control system, a motor, a generator for supplying voltage to said motor, means for variably exciting said generator to cause said motor to be operated at speeds corresponding thereto, and means for cumulatively compounding said generator, between restricted load limits, said compounding means comprising a main-field-pole-supporting frame on said generator, commutating poles on said generator spaced from their supporting frame by non-magnetic gaps and bolts of magnetizable material of predetermined cross section for securing said poles to said frame.

4. In a motor-control system, a motor, a cumulatively-compound-wound generator for supplying voltage to said motor, means for variably exciting said generator to cause said motor to operate at speeds corresponding thereto, and additional means for cumulatively compounding said generator, between restricted load limits, said compounding means including a main-pole-field-supporting frame on said generator, commutating poles for said generator spaced from said frame by gaps composed of non-magnetizable material, and magnetizable means of less cross sectional area than said poles for bridging said gaps.

5. In a motor-control system, a motor, a cumulatively-compound-wound generator for supplying voltage to said motor, means for variably exciting said generator to cause said motor to operate at speeds corresponding thereto, and additional means for cumulatively compounding said generator, between restricted load limits, said compounding means comprising a main-field-pole-support-

ing frame on said generator, commutating poles on said generator spaced from said frame by non-magnetic gaps, and magnetizable means of predetermined flux-conducting capacity bridging said gaps.

6. In a motor-control system, a motor, a generator for supplying a voltage to said motor, means for variably exciting said generator to cause said motor to operate at speeds corresponding thereto, means for cumulatively compounding said generator for obtaining substantially constant-speed regulation of said motor, and means for supplying an additional cumulative component of excitation for said generator through a restricted range of load values.

7. In a motor-control system, a motor, a generator for supplying voltage to said motor, means for variably exciting said generator to cause said motor to operate at speeds corresponding thereto, means for cumulatively compounding said generator for obtaining substantially constant-speed regulation of said motor, and means for supplying an additional cumulative component of excitation for said generator throughout a restricted range of load values comprising commutating poles and magnetizing windings therefor.

8. In a motor-control system, a motor, a generator for supplying voltage to said motor, means for variably exciting said generator to cause said motor to operate at speeds corresponding thereto, means for cumulatively compounding said generator for obtaining substantially constant-speed regulation of said motor, means for supplying an additional cumulative component of excitation for said generator comprising commutating poles and magnetizing windings therefor, and means for limiting the cumulative effect of said additional means to a restricted range of load values.

In testimony whereof, I have hereunto subscribed my name this 27th day of March, 1928.

WILLIAM F. EAMES.
